UNITED STATES PATENT OFFICE.

IGNATIUS BUCKMAN, OF NEW YORK, N. Y., ASSIGNOR TO LEONYE V. HOWARD, OF NEW YORK, N. Y.

HORN.

1,272,615.

Specification of Letters Patent. Patented July 16, 1918.

Application filed October 1, 1914. Serial No. 864,384.

To all whom it may concern:

Be it known that I, IGNATIUS BUCKMAN, a citizen of the United States of America, and resident of the borough of Bronx, in 5 the county of Bronx and State of New York, have invented certain new and useful Improvements in Horns, of which the following is a specification.

This invention relates broadly to signaling or alarm creating devices, and more particularly aims to provide a device of this 10 class characterized by the essential combination of a vibratable diaphragm, which when vibrated is capacitated for the production 15 of sound waves, an actuator, or impact member, for causing vibrations of the diaphragm, a gear-train for directly operating the actuator, and a manually operable driving means for the gear-train.

20 An important object of the invention is to provide an embodiment thereof which, while employable in connection with land vehicles, air and water craft, and in factories and other fixed locations, is especially valuable 25 in connection with the operation of automobiles and in those other situations where manual operation of the alarm is desirable at unexpected times and for prolonged intervals and in the presence of other 30 mechanisms which must also always be under the control of a single operator, as a chauffeur or the like.

The invention has for one of its objects 35 to provide a simple, efficient, inexpensive, easily attachable and compact alarm device, particularly calculated to obviate the necessity for those refinements of construction and adjustment, as well as to obviate difficulties of assembly and general inaccessibility 40 for repairs, usually found in devices, and especially in manually operable devices, of its general type.

Another important object of the invention 45 is to disclose in connection with the present embodiment a type of thrust-controlled actuator for the gear-train aforesaid, which shall present marked advantages over the form of alternative actuator which would probably from the very presence of said 50 gear-train most obviously suggest itself, to wit, a rack.

Other objects and aims of the invention 55 more or less broad than those stated above, together with the advantages inherent, will be in part obvious and in part specifically

referred to in the course of the following description of the elements, combinations, arrangement of parts, and applications of principle constituting the invention; and the scope of protection contemplated will appear from the claims. 60

Referring now to the accompanying drawings, which are to be taken as a part of this specification, and wherein is shown as a preferred form of the invention the embodiment thereof above mentioned: 65

Fig. 1 is a perspective view of said embodiment, certain of the parts being shown in broken lines;

Fig. 2 is a vertical axial section view, 70 showing in broken lines certain of the parts shown in Fig. 1;

Fig. 3 is a detail perspective view, showing on an enlarged scale a type of gear-train driving means as at present preferred; 75

Fig. 4 is a view in perspective, partially broken away, and illustrating the disclosure of Fig. 1 as it would be viewed if observed in the direction of the arrow 4 and if the casing 47 were removed; 80

Fig. 5 is a view similar to Fig. 4, but illustrating the disclosure of said Fig. 1 as it would be viewed if observed in the direction of the arrow 5; and

Fig. 6 is a generally diagrammatic view 85 which will be hereinafter referred to in connection with an analysis of the peculiar function of the various pawls 37, 38 and 39 relatively of the ratchet 27.

Similar references refer to similar parts 90 throughout the several views of the drawings.

As will be understood, the invention may be embodied in various specific and differing forms; for instance, I prefer to employ 95 a horn 7 in connection therewith, though any form of a resonant amplifier may be employed. As shown best in Fig. 2, the narrow or inner end of the horn 7 is mounted about an annular flange 8 that surrounds 100 a central opening 9 punched out from the dish 10. Flange 8, it will be seen, is preferably flared into parallelism with the sidewall of the horn and this serves to anchor the latter firmly in position. 105

The bed-plate 11 (which could perhaps most economically be die-cast) serves a variety of functions. First, it cooperates with dish 10 to clamp therebetween, as by means of the bolts 12, a diaphragm 13; the 110

bed-plate and certain of said bolts in turn coöperate rigidly to attach a supporting bracket 14. Also, this bed-plate carries two sets of companion lugs 15 and 16, each set serving to constitute anchorages upon which may be mounted one of a pair of parallel wall-members 17 and 18, these wall-members here serving to support all operating parts of the alarm-creating elements except the diaphragm. The bed-plate is provided with an opening 19, located between the lugs and of sufficient dimensions to permit the diaphragm-actuator, here the cam 20, to engage with a button 21 or equivalent means preferably centrally carried by and protuberant from the rear face of the diaphragm. With reference to the opening 19, wall-member 17 is, as shown in Fig. 4, mounted adjacent the off sides of lugs 15, and wall member 18 is, as shown in Fig. 5, mounted adjacent the high sides of lugs 16. At this point it may be stated that this "off-side" mounting of wall-member 17 is particularly valuable from the standpoints of convenience, of assembly and disassembly and accessibility for repairs, as hereinafter more in detail pointed out.

When thus positioned, these wall-members serve to support the terminally journaled shafts 22, 23, 24 and 25. Shaft 22 fixedly carries thereon a gear 26 and a ratchet 27. Shaft 23 fixedly carries thereon a pinion 28, meshing as indicated in Fig. 2 (pinion 28 not being disclosed in Fig. 1) with gear 26; said shaft 23 fixedly carrying also a gear 29. Shaft 24 fixedly carries thereon a pinion 30, meshing with gear 29; said shaft 24 fixedly carrying also a gear 31. And shaft 25 carries fixedly thereon a pinion 32, meshing as indicated in Fig. 2 (pinion 32 not being disclosed in Fig. 1) with gear 31; said shaft 25 fixedly carrying also a cam 20.

As indicated by the arcuate arrows shown in Fig. 2, it will be seen that when the ratchet 27 is driven in a clockwise direction, cam 20 is driven in an anti-clockwise direction; from which fact, and from an examination of the oblique terminal face carried by the free end of button 21, it will follow that when ratchet 27 is driven as aforesaid, the peripheral conformations of the cam will cause displacements of the diaphragm and permit free returns of the latter, the rapidity of succession with reference to these alternate displacements and returns being governed by the number of said conformations which are forced past said button within a given interval of time. It will be seen, too, that if this rapidity of succession be equal to a certain minimum, the waves thus generated by the vibratory movements of the diaphragm will generate an alarm having a definite and continuous note.

Before taking up a description of the driving-means for the gear-train, which

driving-means, when taken in connection with ratchet 27, may indeed be said to constitute the most important and novel feature of the present embodiment, an examination of the various figures will disclose that, of the shafts 22, 23, 24 and 25, the first three are provided with opposite terminal portions adapted to be journaled, preferably with merely a loose running fit, within holes bored transversely of the wall members 17 and 18. Shaft 25, however, at least so far as the disclosure of this embodiment of the invention is concerned, while provided with opposite terminal portions similar to those of the first three shafts mentioned except that these terminal portions of said shaft 25 are adapted to project a suitable distance beyond the outer surfaces of wall members 17 and 18, is preferably journaled within a yielding bearing established partially by the slots 33 (see Figs. 4 and 5), the width of each of these slots being preferably just equal to the diameter of the journal holes for shafts 22, 23 and 24, said yielding bearing being further established by an associated leaf-spring 34. The reason for this is to admit, if desired, of a slight yielding or vibratability during working on the part of the cam 20; in the first place, because it is generally accepted in the art that for the best results it is desirable that the diaphragm during actuation shall have vibrations of sufficient amplitude to give forth a loud tone and yet shall at the same time have present a latent insurance available against the possibility of friction between the button and the cam becoming so great as to require more than a convenient amount of power for driving said cam; and in the second place, because such a or an equivalent mounting for shaft 25 is adapted to render less important those minute adjustments, and means of adjustments, which otherwise would be designed so exactly to set the center of cam 20 with reference to the tip of button 21 that a very precise relation is set up between the two, at least initially and before one or the other has become sufficiently worn to throw out the accuracy of such adjustments.

Wall-members 17 and 18, in addition to the journaling accommodations for the four shafts aforesaid, are each provided with a pair of elongated slots, the presence of which are merely indicated in Fig. 1. With the wall-members properly mounted upon their supporting lugs, these four slots arrange themselves into two horizontally disposed sets of opposed slots which are alined parallel with the said four shafts. These sets of slots coöperate with four terminal tongues 35 (but two of which are shown in Fig. 1) which are integrally carried by struts 36. It is these struts which, by means of the transverse preferably vertically alined openings formed therein as shown, guide an actuating

rod 36 for longitudinal travel relatively of said struts. As will be seen from an examination of the broken lines disclosed in Fig. 3, both of these strut-openings are non-continuous, to permit passages transversely of the struts of any of the pawls mentioned in the next following paragraph.

The lower portion of this rod 36, as perhaps best shown in Fig. 3, is centrally and longitudinally slotted so as to establish a bifurcation within which are pivotally mounted any desired plurality of pawls adapted to coöperate with the ratchet 27. In the present instance, three of these pawls are disclosed as being present; although in practice it has been found that the presence merely of two of such pawls renders the combination exceedingly efficient for the attainment of a properly prolonged warning during a single downward and comparatively short thrust of the rod 36. These three pawls may be respectively numbered, for future reference, 37, 38 and 39. Preferably associated with each pawl is a stop-pin 40. Pawls 37, 38 and 39 are spring-urged against their respective stop-pins by means of leaf-springs 41, 42 and 43.

Detachably connected to the upper terminus of rod 36 is an auxiliary portion 36'; this auxiliary portion carrying a finger piece or operating-plate 52.

Bow-spring 44 here serves to return rod 36 to its normal elevated position after each depression thereof, this spring at one terminus being wound about a stud 45 extended from the inner surface of wall-member 18 and at its other terminus being wound about a stud 46 offset from the rod.

The casing 47, preferably being formed as shown in broken lines in Fig. 1, is provided with a suitable squared opening in the curvilinear side-wall thereof through which upwardly projects rod 36; and said casing, in the rim portion thereof which surrounds its mouth, is apertured so that the screws 48 (see Fig. 1) may coöperate with the tapped recesses 49 formed in bed-plate 11 (see Fig. 2).

Let us now consider the coöperation during working between the pawls 37, 38 and 39 and the ratchet 27. It may be stated that preferably pawl 39, which is the pawl that at each thrust of the rod 36, must first overcome the inertial condition of the mechanism, is so disposed normally that its operating tip is in engagement with a ratchet tooth located just below the center of the ratchet, that is to say, if a line perpendicular to the line of thrust of rod 36 be drawn to pass through the center of said ratchet, the tip of pawl 39 is located slightly below this perpendicular line. An analysis of Fig. 6 and an examination of its various delineations is now in order. Let the line T represent the direction of thrust 36. It will be

seen that while the tip of pawl 39 is advancing to the location 39', at which location the stop-pin associated with said pawl will cause the same to leave engagement with the ratchet, the distance traveled by the rod is only equal to the length of the line A; yet the distance simultaneously traveled by the ratchet tooth aforesaid is seen to be not only represented by the chord B, which chord, by the hypotenuse rule, is considerably longer than the line A, but the distance last-mentioned is also represented by the arc C subtending said chord, which arc in turn is considerably longer than the chord itself. The result is that a comparatively short thrust of rod 36 is effective to impart to the ratchet a sufficient peripheral velocity to overcome, not only its inertia and the inertia of its associated members, but the frictional conditions associated therewith. It will be noted from Fig. 6 that according to the design of the present embodiment, when tooth 39 has reached the location 39', the tooth 38 has just entered location 38', that is, is entering into engagement with ratchet 27. This last-mentioned engagement takes place after the ratchet and its driving parts are under the impetus of the momentum established by pawl 39, and so the load submitted to pawl 38 is comparatively small. While pawl 38 is advancing from the location 38' to the location 39', at which location the stop-pin associated with said pawl will cause the same to leave engagement with the ratchet, the distance traveled by the rod is only equal to the length of the line A'; yet the distance simultaneously traveled by the ratchet tooth just mentioned is seen to be represented by the chord D, which chord (although merely equal to the length of the line A', if the line F passing from the center of ratchet 27 as aforesaid be in the present embodiment perpendicular to the line T) is considerably shorter than the arc subtended by said chord and which represents the distance traveled by the pawl. Let the line A' be transferred in location to the position A'', let the curvilinear distance defined by the arc C be represented as a straight line drawn as line C', and let the curvilinear distance defined by the arc subtended by the chord D be represented also as a straight line in prolongation of line C' and drawn as line D'. It will be observed that the line C D now represents the distance through which in longitudinal travel the rod 36 would be compelled to be depressed, were the same a rack and were ratchet 27 a coöperant gear, to cause the fractional rotation of cam 20 now being considered; whereas to cause an equal rotation of said cam the present rod 36 is only compelled to be depressed a distance represented by the length of the line A A. The question might arise, why not just as well

have the initially-acting pawl, that is, the pawl that overcomes the inertial conditions aforesaid, commence its work adjacent the location 38', since the hypotenuse rule 5 would enter with equal force with reference to the line G? But in this connection it may be stated that, while it is believed a certain degree of efficiency would be attained also under the circumstances stated in the 10 query, the preferable construction is the one illustrated in Figs. 1 to 6 inclusive, for the reason that in the latter case the leaf-spring associated with the initially-acting pawl 38 subtracts from, rather than adds to, the burden of depressing the rod 36, and because in the latter case the thrust of this pawl 38 is tangentially, rather than centripetally, applied. Of course, it will be understood that the presence of the third pawl 37 permits 15 the graphic representation of the line A A to become prolonged by the addition thereto of only the line H (equal in length to the line A'), while the graphic representation of the line C D is prolonged in greater 20 degree by the addition thereto of the line J (equal in length to the line D').

It will thus be seen that the present embodiment of the invention, as compared with an embodiment thereof including a rack as 25 a substitute for the pawls 37, 38 and 39, provides a comparatively short thrust for rod 36 to establish a note of any selected prolongation; and, as a result thereof, permits the retention of a gear-train having 30 only the velocity ratios which would be present were there employed a rack having a working surface considerably longer than the straight-line distance between the tips of pawls 37 and 39. In other words, if it 35 is desired to keep the dimensions of the casing 47 at such a minimum that the downward thrust of rod 36 should not exceed the length of the line A A a rack could not be employed; provided the same selected 40 prolongation of the warning is required; for it is clear that were a rack employed to this end and yet delimited in its length of thrust to the value of the line A A, either additional gears would have to be inserted 45 in the train or the velocity ratios in said train radically rearranged. The result of this would be to enlarge beyond desirable 50 limits the dimensions of casing 47, as well as possibly to increase the friction within 55 the gear-train. Moreover, it has been found in practice that the friction encountered during coöperations between ratchet 27 and the pawls 37, 38 and 39 is negligible; whereas the friction created during coöperations 60 between a rack and a coöperant gear is by comparison very high.

Another important advantage resident in the provision of the type of driving means illustrated in Fig. 3 is that a ready means 65 is provided for predetermining a warning

which will be characterized by a note of alternate rising and falling characteristics; for it is obvious that if, longitudinally of rod 36, pawl 39 is spaced sufficiently ahead of pawl 38, and pawl 38 correspondingly ahead of pawl 37, there will occur during a single depression of rod 36 at a uniform rate, first, a rising characteristic when pawl 39 commences to drive ratchet 27, next a falling characteristic immediately following the passage of said pawl 39 from beyond the ratchet, next a rising characteristic when pawl 38 next commences to drive ratchet 27; and so on—these rising and falling characteristics being determined solely by the number of pawls mounted on rod 36 and the spacings of said pawls longitudinally of the rod.

Before closing this specification, attention is directed to the simplicity of the entire structure of the disclosed embodiment. In assembling the parts directly or indirectly carried by lugs 15 and 16, it is a simple matter to mount upon lugs 15 the wall-member 18; then to terminally journal within wall-member 18 one end of each of the shafts 22, 23, 24 and 25; then, after sleeving struts 35 about rod 36, to insert a terminal tongue 35' of each strut within the slots formed in said wall-member 18; then to lay wall-member 17 over the free termini of said shafts and the free tongues of said struts so that the holes and slots formed in said wall-member 17 will engage said shafts and struts; then to insert and tighten the two screws 50; then to insert leaf springs 34 (Figs. 4 and 5) and then to loop one end of bow-spring 44 about stud 45 and the other end of said spring about stud 46. With the auxiliary portion 36' of rod 36 separated, or kept separated, from the latter, the rod is normally depressed sufficiently to allow the mouth of casing 47 to be passed transversely of said rod. The mouth of the casing is then advanced toward bed-plate 11 to come into contact therewith, the upper terminus of rod 36 having in the meantime been by the bow-spring 44 urged to ride against the inner surface of the side-wall of the casing. The casing is then rotated about an imaginary prolongation of the axis of the horn until the square hole formed in the casing overlies the top of rod 36, whereupon the bow-spring will cause the said rod to pass transversely through said opening and protrude normally thereabove. It is necessary then merely to insert and tighten the screws 48 and connect as shown the rod 36 with its auxiliary portion 36'.

Inasmuch as many changes could be made 125 in the above construction, and many apparently widely differing embodiments of my invention could be made without departing from the scope thereof, it is intended that all matter contained in the above de- 130

scription or shown in the accompanying drawings shall be interpreted as illustrative and not in a limiting sense.

It is also to be understood that the language used in the following claims is intended to cover the generic and specific features of the invention herein described and all statements of the scope of the invention which as a matter of language might be said to fall therebetween.

10 Having described this invention what I claim and desire to secure by Letters Patent, is:

1. In a mechanical horn, a vibratable diaphragm, a movable impact member therefor, said impact member when moved being adapted to cause vibrations of said diaphragm, a ratchet operatively connected with and adapted to drive said impact member, a plurality of pawls, a movable support for said plurality of pawls, said support being spring-pressed to a certain position and having an edge facing the impact member and beyond which the pawl tips project, and a guiding means for said support, and means adapted during movement of said support to bring about, first, a coöperation between one of said pawls and one of the teeth carried by said ratchet thereby to rotate the ratchet, and, next, a coöperation between another of said pawls and another of the teeth carried by said ratchet thereby further to rotate said ratchet, said pawls being urged to project their tips toward said ratchet and farther beyond said edge of the support than the shortest perpendicular distance between a portion of said ratchet and said edge.

2. In a mechanical horn, a vibratable diaphragm, a movable impact member therefor, said impact member when moved being adapted to cause vibrations of said diaphragm, a ratchet operatively connected with and adapted to drive said impact member, a plurality of pawls, a movable support for said plurality of pawls, said support being spring-pressed to a certain position, and a guiding means for said support, and means adapted during movement of said support to bring about, first, a coöperation between one of said pawls and one of the teeth carried by said ratchet thereby to rotate the ratchet, and, next, a coöperation between another of said pawls and another of the teeth carried by said ratchet thereby further to rotate said ratchet, said guiding means limiting to a substantially straight line the movement of said support.

3. In a mechanical horn, a vibratable diaphragm, a movable impact member therefor, said impact member when moved being adapted to cause vibrations of said diaphragm, a ratchet operatively connected with and adapted to drive said impact member, a plurality of pawls, a movable support for

said plurality of pawls, said support being spring-pressed to a certain position, and a guiding means for said support, and means adapted during movement of said support to bring about, first, the coöperation between one of said pawls and one of the teeth carried by said ratchet thereby to rotate the ratchet, and, next, a coöperation between another of said pawls and another of the teeth carried by said ratchet thereby further to rotate said ratchet, said guiding means limiting to a substantially straight line the movement of said support and said straight line being substantially perpendicular to a line passing through the center of the ratchet and the point whereat, with the said support located in its said spring-pressed position, there is initiated the coöperation first above-mentioned.

4. In a mechanical horn, a vibratable diaphragm, a movable impact member therefor, said impact member when moved being adapted to cause vibrations of said diaphragm, a ratchet operatively connected with and adapted to drive said impact member, a plurality of pawls, a movable support for said plurality of pawls, said support being spring-pressed to a certain position, and a guiding means for said support, and means adapted during movement of said support to bring about, first, a coöperation between one of said pawls and one of the teeth carried by said ratchet thereby to rotate the ratchet, and, next, a coöperation between another of said pawls and another of the teeth carried by said ratchet thereby further to rotate said ratchet, said guiding means limiting to a substantially straight line the movement of said support; said pawls being spring-urged to project their tips away from said straight line and toward the teeth of said ratchet.

5. In a mechanical horn, a vibratable diaphragm, a movable impact member therefor, said impact member when moved being adapted to cause vibrations of said diaphragm, a ratchet operatively connected with and adapted to drive said impact member, a plurality of pawls, a movable support for said plurality of pawls, said support being spring-pressed to a certain position, and a guiding means for said support, and means adapted during movement of said support to bring about, first, a coöperation between one of said pawls and one of the teeth carried by said ratchet thereby to rotate the ratchet, and, next, a coöperation between another of said pawls and another of the teeth carried by said ratchet thereby further to rotate said ratchet; said support having associated therewith a bow-spring adapted to press said support to a certain position.

6. In a mechanical horn, a vibratable diaphragm, a movable impact member therefor, said impact member when moved being

adapted to cause vibrations of said diaphragm, a ratchet operatively connected with and adapted to drive said impact member, a rod-like support, a plurality of pawls supported by and longitudinally spaced along said support, said rod-like support being longitudinally movable in a predetermined path whereby said pawls may in predetermined sequence coöperate with said ratchet to drive the latter.

7. In a mechanical horn, a vibratable diaphragm, a revolute wheel carrying a plurality of spaced conformations, said conformations when said wheel is revolved being adapted to cause vibrations of said diaphragm, a ratchet, a gear-train adapted to be driven by the rotation of said ratchet and

adapted to revolve said wheel, a plurality of pawls, a movable support for said plurality of pawls, and a guiding means for said support, and means adapted during movement of said support to bring about, first, a co-operation between one of said pawls and one of the teeth carried by said ratchet thereby to rotate the ratchet, and, next, a coöperation between another of said pawls and another of the teeth carried by said ratchet thereby further to rotate said ratchet.

20

25

In witness whereof, I have hereunto signed my name in the presence of two witnesses.

IGNATUS BUCKMAN.
